UNITED STATES PATENT OFFICE

148,482

DESIGN FOR A DISPENSING HEAD OR THE LIKE

Ferdinand P. Pla, Buffalo, N. Y.

Application April 15, 1946, Serial No. 128,608

Term of patent 3½ years

(Cl. D58—26)

To all whom it may concern:

Be it known that I, Ferdinand P. Pla, a citizen of the United States, residing at Buffalo, in the county of Erie and State of New York, have invented a new, original, and ornamental Design for a Dispensing Head or the like, of which the following is a specification, reference being had to the accompanying drawing, forming a part thereof.

Figure 1 is a front view of the dispensing head embodying my new design. Figure 2 is a right hand end view thereof. Figure 3 is a rear view of the same. Figure 4 is a bottom plan view of the head. Figure 5 is a top plan view of the same.

I claim:

The ornamental design for a dispensing head or the like, substantially as shown.

FERDINAND P. PLA.
